ATTORNEY

UNITED STATES PATENT OFFICE

173,296

DECORATIVE LIGHTING UNIT

Alfred H. Inman, Jr., Orlando, Fla.

Application January 4, 1954, Serial No. 38,358

Term of patent 14 years

(Cl. D48—20)

To all whom it may concern:

Be it known that I, Alfred H. Inman, Jr., a citizen of the United States, residing at 5 Interlaken Road, Orlando, Florida, have invented a new, original, and ornamental Design for a Decorative Lighting Unit, of which the following is a specification, reference being had to the accompanying drawing, forming part hereof, in which

Fig. 1 is a front elevational view of a decorative lighting unit showing my new design; and

Fig. 2 is a side elevational view thereof.

I claim,

The ornamental design for a decorative lighting unit, as shown.
